UNITED STATES PATENT OFFICE.

ALTON J. SHAW, OF MUSKEGON, MICHIGAN.

RHEOSTAT.

SPECIFICATION forming part of Letters Patent No. 468,752, dated February 9, 1892.

Application filed October 15, 1891. Serial No. 408,794. (No model.)

To all whom it may concern:

Be it known that I, ALTON J. SHAW, a citizen of the United States, residing at Muskegon, in the county of Muskegon and State of Michigan, have invented certain new and useful Improvements in Rheostats, of which the following is a specification.

My invention relates to rheostats or artificial resistances for employment in connection with electrical apparatus; and it consists in a novel construction of the same, hereinafter fully set forth, by which I am enabled to obtain any required degree of resistance and to vary the same quickly, uniformly, and with certainty without the liability of dangerous heating, burning out, or sparking.

Figure 1 is a perspective view of a rheostat embodying my improvements; Fig. 2, a side elevation partly in section; Fig. 3, an enlarged sectional view illustrating the construction of the snap-switch; Fig. 4, an end view of the same, and Fig. 5 a cross-section on the line $x-x$ of Fig. 2.

Briefly stated the rheostat consists of a solid or integral bar, either straight or curved, and preferably of carbon, a mixture of carbon and clay or other inferior conductor suited to the particular use in view, and a series of transverse plates embedded in and constituting an integral part of the complete bar, but projecting above the main body thereof sufficiently to form contact points or surfaces for the brushes, springs, or other contact devices to bear upon. Prior to my invention rheostats have been made in a variety of forms, and carbon, clay, steatite, and various other materials, as well as compositions of different materials, have been employed to give the desired resistance. So, too, plates of metal or alloy, either of one or two varieties, have been bound together or held in permanent contact, so as to constitute in effect one continuous bar, certain plates of the series being arranged to project and form the contact-surfaces. In the use of carbon, clay, and compositions of these and analogous substances a difficulty has been encountered which I aim to overcome by my invention, and that is the heating of the contacts when such have con-

prior constructions, if the current passed is heavy, bars of considerable cross-section must be used, and as they must have a high specific resistance current entering at the side 55 of the bar will not distribute itself throughout its entire area or mass, but will tend to pass along one side of the bar. The seemingly obvious remedy for this difficulty is to make the bar of a lower specific resistance 60 transversely than longitudinally; but if the bar be made homogeneous this cannot be done; but by my construction this desirable result can be attained with ease and certainty. By embedding in the bar plates of 65 metal, pure carbon, or other substance having a lower specific resistance than the body of the bar itself I insure the distribution of the current throughout the area of said plate, and consequently throughout the body 70 of material intervening between each plate and the next, and thus overcome at once the two difficulties above indicated—viz., the heating and the unequal distribution of the current throughout the mass of the bar.

Referring again to the drawings, A indicates the resisting bar or body of the rheostat, which I prefer to make in one homogeneous mass, and B plates of metal, pure carbon, or other suitable material embedded in and 80 constituting an integral part of the complete bar. The bar may be of any desired form in cross-section, and the plates are ordinarily conformed more or less closely to the section of the bar, though I prefer that the lower and 85 side edges of the plates be surrounded by or inclosed in the body of the bar A, as best shown in Fig. 5.

In practice I find a composition of carbon and clay admirably suited to the purpose 90 stated, the specific resistance varying as the proportions of carbon and clay are varied, increasing and decreasing in direct consonance with the decrease or increase in the relative proportion of clay used.

As the requirements of the art call for a very wide range and as the proper proportions for different uses are already well understood, I do not mean to restrict myself to any definite proportions whatever, nor, in 100 fact, to the use of these particular materials, but propose to use any material or composi-

tion of materials now known as suitable to the purpose, but may say that for ordinary purposes equal parts of carbon and clay may be advantageously used. These materials are 5 moistened and worked together with water or with any suitable liquid or binding agent and preferably pressed into shape in a mold containing the plates B, suitably spaced; but obviously the plates may be inserted into the 10 bar after it has assumed its form, but before it has become solidified. The bar may be dried with or without pressure or may be baked, or, as I prefer, it may be first firmly compressed and then baked to render it more durable. If desired, the mixture may be 15 treated in any well-known manner to eliminate or to render practically incombustible any combustible elements that may be present.

20 Pure carbon in the free state—as, for instance, in the form of graphite—is infusible. Various compounds of carbon and other substances are combustible; but by first washing with sulphuric acid, gas-coke, graphite, or 25 other forms of carbon containing more or less of impurities and subsequently removing all trace of acid by thorough washing in water I am enabled to obtain a grade of carbon well suited to the purposes of this invention. Such 30 treatment is not claimed by me; nor is it deemed necessary ordinarily. By mixing ordinary gas-retort carbon in the form of powder with clay a very satisfactory composition is obtained.

35 As shown in Figs. 1, 2, and 3, the plates B have their upper ends bent laterally, so as to afford a broad flat bearing-face for the contact fingers, springs, plates, toes, or brushes, as the case may be, which are indicated in the 40 drawings by the letter C. In practice I prefer a series of gravitating toes hung upon a common rod or pivot, as shown in Figs. 1 and 2, the pivot-rod being carried by a sliding block or head D, which may be guided upon 45 rods E or in any other convenient manner, the block or the rods, one or the other, being duly insulated. It is desirable in this class of devices that when the contact toes, brushes, or springs leave the last plate or contact of 50 the series the break shall be quickly made and of such width as to prevent sparking. Various devices to this end have been devised, and these are known under the general name of "snap-switches." Such a device is provided in my rheostat and is formed by hinging the last plate F of the series and holding it normally in its upright position by 55 means of a spring, weight, or other device, a spring being preferred because of its quicker 60 action.

The construction referred to is illustrated in Figs. 2 and 3, in which the last plate but one of the series is represented as attached to or provided with a supplemental plate B', having a lug or extension b, which projects through the end of the bar and forms a bear-

ing for the last plate F of the series. The supplemental plate B' is formed with ears c, between which the lower end of the last plate is hinged or pivoted, as shown in Figs. 1, 2, 3, 70 and 4, a spring bearing against the outside face of the plate F and serving to hold it normally in an upright position and in contact with the lug b.

In Fig. 2 I have represented a spring H in 75 spiral form encircling a rod or stem, the inner end of which screws into the bar A or into the plate B', while its head or outer end forms a bearing for one end of the spring.

In Fig. 3 I have shown a flat spring H', the 80 lower end of which is secured to the lower end of plate B'; but it is apparent that the precise arrangement of the spring is immaterial, as is also its form.

I prefer to make the plates with openings, 85 one or more, as shown in Fig. 5 and as indicated by dotted lines in Fig. 4, so that when they are embedded in the plastic material of which the bar is formed said material shall pass through the openings and serve not only 90 to firmly hold the plates in place, but also to make the bar homogeneous and continuous from end to end. In this way I insure a more perfect distribution of the current over the entire sectional area of the bar than is otherwise practicable.

The form, size, and number of the openings of the plates are immaterial and may be varied, as desired. Binding-posts, clamps, or other convenient means of connection for the line-wires will be provided for the first plate B of the series and for the contact toes, springs, or plates C.

The bar A may be secured upon a piece of wood or other suitable material or otherwise 105 held in place, and, as above mentioned, may be either straight or curved, and the curvature may be in any direction desired.

The plates B are preferably made of iron and will in practice be struck up or stamped 110 from sheet metal.

It is desirable to employ in connection with the bar A of carbon or other composition transverse plates of some material having the same or substantially the same relative 115 expansion and contraction under changes of temperature, in order that the contact may be preserved and kept uniform, and in order, further, that the bar may not be broken or destroyed by more rapid expansion of the plates 120 than of the bar. For this reason it may in some cases be desirable to use pure carbon plates instead of metallic plates; but by careful selection from well-known metals and compositions it is entirely feasible to make such 125 combinations as shall avoid any difficulty which might possibly arise through injudicious combinations.

As the rates of expansion and contraction of almost all known substances have been determined and tabulated and as I do not in 130 any manner restrict myself to any particular

combination of substances or materials it is deemed unnecessary to specify any particular combination.

Having thus described my invention, what

5 I claim is—

1. In a rheostat, an integral bar or body constituting the resistance and a series of plates embedded in said bar at points between its ends and projecting therefrom at one side to 10 form contact-surfaces, the plates being of lower specific resistance than the body of the bar.
2. An integral resistance bar, block, or body consisting of a main body of comparatively 15 low conducting-power and a series of transverse plates embedded in said body at intervals throughout its length, said plates having a lower specific electrical resistance than the material composing the main body.
- 20 3. The herein-described resistance bar or block, consisting of a body A of material of comparatively high specific resistance and a series of transverse plates B of material having lower specific resistance than the body A, 25 said plates projecting from the bar and having their ends bent over to form contact-surfaces, substantially as shown and described.
4. In a rheostat, the combination of a molded integral body A and transverse distributing-

plates B, the plates being formed with one or 30 more openings from face to face and the substance of the bar passing through and filling said opening, substantially as shown and described.

5. In combination with bar A, provided 35 with plates B, end plate F, hinged to swing away from the end of the bar, a spring bearing against said plate and serving to hold the same normally against the end of the bar, and a movable contact arranged to ride over the 40 plate B in succession and to move the plate F away from the end of the bar and finally to pass out of contact with said plate and permit its quicker return to its normal position.

6. In combination with bar A and plates B, 45 movable contact C, hinged plate F, and spring H, serving to hold the plate F normally in an upright position.

7. In combination with bar A, provided with plates B, plate B', provided with lug a and 50 ears b, plate F, hinged in said ears, spring H, and movable contact C.

In witness whereof I hereunto set my hand in the presence of two witnesses.

ALTON J. SHAW.
